UNITED STATES PATENT OFFICE.

FIDEL FEEDERLE, OF OBERNDORF-ON-THE-NECKAR, GERMANY, ASSIGNOR TO Waffenfabrik Mauser, Aktiengesellschaft, of Oberndorf-on-the-Neckar, Germany.

MAGAZINE RIFLE OF SMALL CALIBER.

Application filed March 8, 1923. Serial No. 623,710.

To all whom it may concern:

Be it known that I, FIDEL FEEDERLE, citizen of the German Republic, residing at Oberndorf-on-the-Neckar, Germany, have 5 invented certain new and useful Improvements in Magazine Rifles of Small Caliber, of which the following is a specification.

My invention relates to a magazine rifle of a small caliber and provided with a bolt 10 breech mechanism.

The primary object of my invention is to provide a rifle of the above indicated type that is extremely simple in construction, strong and durable and highly practical inasmuch as disturbances or accidents such as 15 jamming of the cartridges or the like are reduced to a minimum.

Another object of my invention is to provide improved means for a ready change of 20 the magazine and for a high degree of safety. Various other objects and advantages will become apparent during the course of the following description.

These objects are accomplished by such 25 means as are shown in their preferred form in the accompanying drawings, described in the following specification and thereafter more specifically pointed out in the appended claims.

30 In the accompanying drawings wherein like characters designate like parts throughout the several views:

Figure 1 is a partial vertical longitudinal section of a rifle with the firing rod cocked; 35 Figure 2 is an end view thereof; Figure 3 is a bottom view of the bolt; Figures 4 and 5 are sectional views on the lines IV-IV and V-V, respectively, of Figure 3; Figure 6 is a side view of the casing or sleeve; Figure 40 7 is a section on the line VII-VII of Figure 6; Figure 8 is a top view of the bolt and the firing rod casing connected therewith; Figure 9 is a partial vertical longitudinal section of the rifle with the breech opened; 45 Figure 10 is a section on the line X-X in Figure 9; Figure 11 is a side elevation of the magazine, partly in section; Figure 12 is a top view thereof and Figure 13 illustrates in a similar view a detail of the magazine; Figure 14 is a partial vertical longi-

tudinal section of the rifle to illustrate the particular construction of the safety mechanism, showing the latter in the open or firing position and Figure 15 is a similar view showing the safety mechanism in the locking or "safe" position; Figure 16 is a cross-section taken on the line XVI-XVI of Figure 15; and Figures 17 to 19 are views of the safety device separately, Figures 17 and 18 being side views and Figure 19 a sectional view thereof. The front portion of the bolt 1 is of an essentially smaller diameter than the rear portion thereof, two longitudinal parallel recesses 2 and 3 being cut in the wall of said front portion with their inner ends sloping into the outer face of the bolt. Intermediate the two recesses 2 and 3 a ridge 4 is formed at the bottom side of the bolt, said ridge being adapted to project between the lateral lips 5 of the magazine 6, when the bolt is in its retracted or open position, as will be clearly understood from an inspection of Figures 9 and 10. It will be seen that the lips 5 of the magazine 6 engage in the recesses 2 and 3, so that the upper rim of the magazine and the uppermost cartridge therein lie in the closest possible proximity to the axis of the barrel. In this manner a means is provided for readily and properly introducing the cartridge into the 65 cartridge chamber of the barrel.

The casing or sleeve 7, Figures 6 and 7, in which the bolt 1 is guided during its reciprocal movements for reloading the rifle, is closed at the top and has, as usual, in the 70 forward end of its right hand wall an opening 8 for the ejection of the spent cartridge shells and a longitudinal slot 9 terminating in an enlarged rectangular opening 10 for locking purposes. When unlocked the 75 handle 11 of the bolt assumes a horizontal position, as shown in dotted lines in Figure 10, and in such position the handle is in alignment with the slot 9, so that the breech can be opened in the usual manner by withdrawing the bolt by means of the handle. When locked, however, the handle 11 assumes the depending position shown in Figure 2, engaging in the rectangular opening 10. Owing to this construction of the casing 100

or sleeve 7 with an uninterrupted plane upper face any suitable means for the attachment of a field glass or other appropriate sighting device may be readily applied thereto; if a field glass is affixed at the top of the sleeve the opening and closing of the bolt will not be obstructed thereby.

The portion 14 of the bolt is provided with a longitudinal lug or rib 15, as will be seen in Figures 2 and 8, extending over the whole length thereof. When the breech is closed the said lug 15 engages in the slot 9 of the sleeve to the full of its length, but even when the breech is opened the lug still remains in engagement therein to a certain extent, so that the portion 14 and the firing mechanism located therein are prevented from being rotated.

The magazine 6 of the rifle has the rear bottom corner shaped to form an incline 16, Figure 11, adapted to co-operate with a correspondingly inclined face of the pivotally mounted magazine holder 17, Figures 1 and 9. This construction permits the magazine to be removed from the rifle by simply drawing or pressing the same backwards towards the holder 17 since the latter then recedes so that the co-acting faces disengage and the magazine will be free to drop out of its housing.

The holder 17 is provided with a spring acting in such a manner that the lips 5 of the magazine, when the breech is opened, will be forced to engage in the recesses 2 and 3 of the bolt, whereas when the breech is closed, that is to say, when the bolt 1 is caused to advance from its position shown in Figure 9 towards the left-hand side, the magazine will be free to escape downwards, as soon as the rear sloping ends of the recesses 2 and 3 pass over the said lips 5 and the latter come in contact with the un-recessed smooth face of the forward portion of the bolt. When the parts under consideration assume this position the bolt can be turned so that the handle 11 will be brought into locking engagement with the forward wall of the opening 10, Figure 7, in order to adopt the position shown in Figure 2, irrespective of the recesses 2 and 3 which cannot interfere. At the operation of opening the breech the magazine is automatically lifted by the spring-actuated holder 17 into its upper position with the lateral lips 5 engaging in the recesses 2 and 3 of the bolt.

The lips 5 of the magazine are so constructed as will be seen in Figure 12, that the mouth formed between them decreases in width towards their forward ends. The result thereof is that, particularly if rim-fire cartridges are employed, the uppermost cartridge, in ascending into the sleeve or casing 7, Figure 9, assumes a gradually more and more inclined position with respect to the cartridge chamber of the barrel, since

the rim of the cartridge, in moving forwards between the two lips 5, is lowered more and more owing to the decreasing width of the mouth. In this way a high degree of reliability is ensured in driving the uppermost cartridge into the chamber of the barrel and the danger of jamming is reduced to a minimum.

Obviously, if rim-fire-cartridges are employed the lower cartridges in the magazine necessarily must lie in a more declined position than any upper ones. In order to avoid any undesired play or clearance which would result in causing the cartridge rims to not lie properly superposed one over the other, the magazine is given a tapered shape, that is to say, it is, as regards its width, smaller at the bottom than at the top, as will be clearly seen from Figure 11. In order that the rims of the cartridges in the magazine may lie in front of each other, the magazine is given a particularly inclined position in the rifle.

The carrier 18 of the magazine is shaped to form a shallow cavity 19, which is of a depth increasing from left to right in Figure 13. The ridge 20 formed at the right-hand end serves the purpose of holding the rims of the superposed cartridges, at least in the lower part of the magazine, a little distance apart from the end wall thereof, so that friction between the cartridge and the magazine wall will be avoided. Owing to this fact a relatively light spring 21 may be employed whereby the operation of refilling the magazine with cartridges will be facilitated.

As will be seen in Figure 11 the carrier 18 is pivotally connected with the spring 21, preferably by bending the upper end of the spring inwards to form the pivot, so that the position of the cartridge carrier 18 will automatically be accommodated to the variations in the direction or relative positions of the lowermost cartridge in the magazine. The direction of the inclined bottom of the magazine corresponds or is adjusted to the position of the lowermost cartridge in the filled magazine.

The safety device for locking the trigger and the bolt in their cocked position is shown in Figures 14 to 19. The device comprises a slide 22 having a knurled thumb-piece. The said slide is mounted on the left side of the rifle adjacent to the sear 23 of the trigger-mechanism and adapted to be shifted lengthwise. As shown in Figures 14 and 15 a spring-controlled locking pin is provided in connection with the slide 22 and the pin is adapted to engage in one or the other of two notches provided in the sleeve, just as the device is put "safe" or not.

The slide 22 has a longitudinal slot in engagement with a stationary pin and is provided at its fore end with a projection or

tooth 24 adapted to rest upon the sear 23, when the slide is set "safe," and to thereby lock the said sear and the trigger, as will be seen in Figures 15 and 16. When the 5 parts have assumed the described positions a nose 25 projecting from the slide 22 upwards in close proximity to the projection 24, engages in a recess 26 in the bolt so that the latter likewise will be locked by the slide. 10 The slide is mounted and located in the rifle in such a manner that any pressure imparted to the trigger either accidentally or on purpose cannot cause the trigger or the bolt to be released, when the slide is set "safe" or 15 in locked position.

A further safety arrangement provided in the rifle consists in a means by which the trigger, if the bolt is not fully locked, will be fixed and unable to be moved. To this 20 end the bolt is provided with another recess or groove 33, Figures 3 and 16, adapted to receive a nose 34 integral with the sear 23 when, and only when, the breech is duly locked as shown in Figure 16. In all cases, 25 however, where the bolt is not correctly locked the nose 34 is in contact, or approximately so, with the peripheral face of the bolt, so that the sear and consequently the trigger cannot be actuated. It will be seen 30 that firing is impossible unless the bolt is completely locked.

Mounted in the bolt is the firing pin 27 having a spring 28 coiled about its rear end to hold the pin normally in a retracted position, as shown in Figure 1. The front end of the spring 28 rests on the bottom of the bore in which the spring is housed, while its rear end is in contact with a disk 29 rigid with the pin and abutting against a nose 30 of the extractor 31 as shown in Figure 1. The spring 28 is more powerful than the spring coiled about the firing rod 32 so that, after the firing impact, the spring 28 acts to force back the rod 32, against the action 40 of the spring coiled thereabout, until the disk 29 again is in contact with the nose 30 of the extractor and the pin 27 reassumes its normal position, as in Figure 1.

It is apparent that in carrying my invention into effect some changes from the construction and arrangements herein shown and described may be made. I wish it therefore to be understood, that I do not limit myself thereto, but hold myself at liberty to make such departures therefrom as may fairly fall within the spirit and scope of my invention.

What I claim is:—

1. A small caliber bolt-breech rifle of the 60 magazine type, comprising a sleeve or casing, a bolt slidably mounted in said casing and having formed in its bottom face, two parallel longitudinal recesses which extend from the front end thereof a certain length 65 and then gradually merge into the periph-

eral surface of the bolt, and a magazine having two lateral lips adapted to engage in said recesses.

2. A small caliber rifle, comprising a sleeve formed at one side with a longitudinal slot which is open at one end and is enlarged at its other end to form a locking seat, a bolt slideable in said sleeve and embodying a front portion of smaller diameter than the rear portion, a longitudinal rib on the side face of the rear portion of the bolt adjacent said slot to slide therein, and a handle on said bolt in advance of said rib likewise adapted to slide in said slot and to be turned into said seat to lock the bolt 75 against movement; substantially as described.

3. A small caliber rifle of the magazine type, comprising a sleeve formed at one side with a longitudinal slot which is open 80 at one end, a bolt slideable in said sleeve and embodying a front portion of smaller diameter than the rear portion, said front portion having formed in its bottom face two parallel longitudinal recesses which extend from the front end thereof for a certain distance and then gradually merge into the peripheral surface of the bolt for the reception of two lateral engaging lips on the magazine, a longitudinal rib on the side face 85 of the rear portion of the bolt adjacent said slot to slide therein, and a handle on said bolt in advance of said rib; substantially as described.

4. A small caliber bolt-breech rifle of the 100 magazine type, comprising a sleeve or casing, a bolt slidably mounted in said sleeve, the bottom face of the bolt having two parallel longitudinal recesses cut therein, a magazine having two lateral lips for engagement in said recesses and having its rear bottom corner shaped to form an inclined face, and a magazine holder having a correspondingly inclined front face to co-operate with the inclined face of the magazine, substantially as set forth.

5. A small caliber bolt-breech rifle of the magazine type, comprising a sleeve or casing, a bolt slidably mounted in said sleeve and having two parallel longitudinal recesses cut in its bottom face, a magazine having two lateral lips for engaging in said recesses and having its rear bottom corner shaped to form an inclined face, and a pivotally mounted, spring-controlled magazine 115 holder having a correspondingly inclined front face to co-operate with the inclined face of the magazine, substantially as and for the purpose set forth.

6. A small caliber bolt-breech rifle, comprising a sleeve, a bolt slidably housed in said sleeve and provided at its lower portion with a recess, a sear, a safety slide, a lateral tooth on one side of said slide adapted to overlie and thereby lock the sear, and 120 125 130

a nose projecting upwardly from said slide immediately adjacent said tooth for engagement in said recess, substantially as and for the purpose set forth.

5 7. A small caliber bolt-breech rifle, comprising a sleeve, a bolt slidingly encased in said sleeve, a spring controlled firing pin in said bolt, a cartridge extractor connected

with said bolt, and a nose at the rear end of said extractor for limiting the rearward movement of the firing pin to normal position, substantially as and for the purpose set forth.

In testimony whereof I affix my signature.

FIDEL FEEDERLE.
